UNITED STATES PATENT OFFICE.

REUBEN F. WILCOX, OF AUGUSTA, KANSAS.

ADDING-MACHINE.

SPECIFICATION forming part of Letters Patent No. 326,824, dated September 22, 1885.

Application filed April 18, 1885. (No model.)

To all whom it may concern:

Be it known that I, REUBEN F. WILCOX, a citizen of the United States, residing at Augusta, in the county of Butler and State of Kansas, have invented certain new and useful Improvements in Adding-Machines; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to adding-machines; and it consists in the novel construction and combination of parts, as will be hereinafter fully described, and particularly pointed out in the claim.

In the drawings, Figure 1 is a plan view of the bottom disk or plate and the internal plate or register of hundreds, and Fig. 2 is a plan view of the top plate. Fig. 3 is a sectional detail view taken on the dotted lines of Fig. 1.

Referring by letter to the accompanying drawings, A designates the base or main plate, which is preferably of annular or disk form, and has a depressed surface, except at the rim B, which is raised above the remaining portion of the surface of the disk A sufficiently to admit the plate C, or register-plate, between the base-plate and the top plate, F. The top plate, F, turns on a central pivot, P, rising from the base-plate A, and is provided with one hundred (100) points, I, and one hundred holes, K, at the bases of said points I. Near its center the top plate, F, is provided with a slot, B', and a catch, T, between the central hole and the slot B' in said plate. The plate F revolves on the central stud or pin. The point marked X on plate F, as seen in the drawings, corresponds with X' on the rim B, or 100, when properly in place, and the addition now begins. As seen in the drawings, 2,700, or the highest number on the register C, now shows

through the slot B'. Then the catch T is now 45 between the central hole and the slot B'. Said catch, being on the under side of said plate F, is free from the register; but as the plate F is turned on around until X and X' come together the little catch T will have caught 50 one of the pins T' on the register C and will have turned the register C one point, leaving 100 in place of the 2,700—viz., in slot B'. The one hundred holes in plate F are for the insertion of the pencil-point to turn plate F. 55 For example, X and X' are opposite. Turn point X by means of a pencil to 20 on A. Then go back with the pencil to X', or 100. Take the point you find there and turn it around to 20. Point X will then be at 40. 60 Continue thus taking the point opposite 100 and turn to any number desired, and point X will advance accordingly, and when it gets around to 100 on the plate A the register will show the amount through the slot B' of plate F. 65

Having thus fully described my invention, what I claim, and desire to secure by Letters Patent of the United States, is—

The calculator described, consisting of the base-plate A, having the raised rim, as shown, 70 provided with numerals from 1 to 100, and the central pivot-stud, P, the top plate, F, arranged on the said pivot, having the peripheral points, each provided with a hole, and the opening B', and the catch T between the said opening and the pivot-aperture, and the register C, pivotally arranged between the base-plate and the revolving top plate, and provided with the peripheral pins T', the whole adapted to operate substantially as 75 specified.

In testimony whereof I affix my signature in presence of two witnesses.

REUBEN F. WILCOX.
